UNITED STATES PATENT OFFICE.

ARLING SHAEFFER, OF CHICAGO, ILLINOIS.

BUFFER STOP-KNOT FOR MUSICAL-INSTRUMENT STRINGS.

SPECIFICATION forming part of Letters Patent No. 674,618, dated May 21, 1901.

Application filed March 18, 1901. Serial No. 51,673. (No model.)

To all whom it may concern:

Be it known that I, ARLING SHAEFFER, a citizen of the United States, residing at Chicago, in the county of Cook and State of Illinois, have invented a new and useful Buffer Stop-Knot for Musical-Instrument Strings, of which the following is a specification.

My invention relates to improvements in the strings of musical instruments, such as the guitar, mandolin, &c., which strings have a tendency to part close up to the stop-knot at the bridge end of the instrument; and my object is to provide a buffer which covers all or a portion of the knot and which serves as a bedding between the knot and the inside surface of the top of the instrument and the retaining-peg, so that substantially an equal strain will be imposed all around the circumference of the string and the intensity of its tension-pressure moment reduced at all times, but more especially when after long use its limit of elasticity has been almost attained, the same being described hereinafter and illustrated in the accompanying drawings, in which—

Figure 1 is a longitudinal section of a portion of the top of a guitar and a cross-section of the bridge with a portion of a string with a buffer-knot and the retaining-pin in side elevation. Fig. 2 is the same as Fig. 1, but shows the stop-knot in the usual position without a buffer. Fig. 3 shows two side elevations of an ordinary stop-knot together with a portion of a string. Fig. 4 is an elevation showing a part of a string with the knot covered with a fine cord closely wound thereon to serve as a buffer and bedding. Fig. 5 is an axial section of a capsule of any fibrous or resilient

material or of any plastic or combination of materials adapted to serve as a buffer or bedding and is shown in position covering the stop-knot in Fig. 6.

Similar letters indicate like parts throughout the several views.

A indicates a longitudinal section of a portion of the top of a guitar, B is a cross-section of the bridge, and C an elevation of the usual retaining-pin D.

The stop-knot E at the end portion of string F may be single, double, or any other form best adapted to serve the purpose, and the knot may be subjected to pressure in a mold to give it a more regular form, if necessary, or may be entirely or partially covered with a resilient or non-resilient cement and then covered with the buffer without the intent of the improvement being altered, which is to insure a practically equal strain at all sides of the string at the retaining-knot in addition to providing a buffer G or H for the purpose stated.

I claim as my invention—

1. The combination with a musical-instrument string having a stop-knot, of a buffer on the said knot, for the purposes hereinbefore stated.

2. In a musical-instrument string having a stop-knot, a buffer on the said knot composed of a yielding material or materials adapted to serve as a buffer and bedding therefor, for the purposes stated.

ARLING SHAEFFER.
